T. LUND.
SOFTENING APPARATUS.
APPLICATION FILED FEB. 4, 1918.

1,355,836.

Patented Oct. 19, 1920.

INVENTOR

Thomas Lund
By his Attorney,
Nelson M. Hinckley

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOFTENING APPARATUS.

1,355,836.

Specification of Letters Patent. Patented Oct. 19, 1920.

Application filed February 4, 1918. Serial No. 215,325.

To all whom it may concern:

Be it known that I, THOMAS LUND, a citizen of the United States, residing at Beverly, in the county of Essex and State of Massachusetts, have invented certain Improvements in Softening Apparatus, of which the following description, in connection with the accompanying drawings, is a specification, like reference characters on the drawings indicating like parts in the several figures.

This invention relates to the manufacture of boots and shoes and in particular to the manufacture of shoes having box toes which are softened by heat in preparation for lasting. The use of box toes of this character has become quite universal. They are sometimes placed in the shoe and then softened prior to the pulling-over operation. They are sometimes softened before incorporation in the shoe, damage to the upper materials by the heating means being thus avoided. This latter practice is called "slipping the boxes," and it is with this that my invention is particularly concerned.

The boxes or "blanks" are softened by placing them on a support heated in any desirable manner. They may be supported in contact with hot steam, or on a "hot plate" heated by steam or electricity. Whatever the softening means adopted, many accidents occur due to burning of the operators' fingers in picking them up. They are impregnated with a substance which is sticky when hot and they adhere to a support on which they are heated. Inasmuch as the blanks are flat and thin, it is difficult to pick them up, and the operators frequently cannot avoid touching their fingers to the heating means in taking them up. It is an object of my invention to provide novel apparatus for heating box toes or similar articles which shall be convenient in use and shall insure against injury to the operator.

To this end an important feature of the invention is a means for separating the heated blanks from the heating means without the necessity or risk of touching the heating means with the fingers. After their separation from the heating means, the

blanks may be safely picked up by the operator. The machine shown comprises a hot plate containing apertures, and a relatively movable member having pins arranged to pass through the apertures to separate the blanks from the hot plate.

According to the construction shown the plate that has the apertures will be heated but the structure that separates the blanks therefrom will not be heated, although these two elements remain always in co-operative relation with the pins in registration with the apertures. Thus, even though the pins are spaced from one another far enough to enable one's thumb or finger to enter between two of them without touching either, and at the same time the pins are sufficiently close to each other to provide adequate support for the blanks, which are limp when heated, no harm can result from touching the fingers to the pins because the latter remain cool. This feature of heating the foraminous plate without heating the pins is obtained by forming the plate with one or more chambers in which the heat may be generated, or through which a heated medium, such as steam, may be circulated. In the present case the heat is generated locally in these chambers by electrical heating elements, thus avoiding the necessity of the more cumbersome steam equipment.

Another important feature of the invention resides in constructing the separating means so as to be operated by the same hand that is used to reach for a heated blank.

These and other features of the invention will be understood from the following description of a preferred embodiment of the invention selected for purposes of illustration and shown in the drawings in which,

Figure 1 is a broken-away perspective view, and Figs. 2 and 3 are sectional views showing the apparatus in two positions.

The base 10 supports a hollow casing 12, the upper wall 11 of which is perforated with numerous holes 14 and is heated to the desired temperature preferably by electric units 16 embedded in a convenient number of bosses 18. These units are wired in any desired manner to the current supply line 20.

The end walls of the chamber have each a pair of vertical guides 22. A plate 24 is arranged with slides 26 at its ends between the vertical guides 22. The plate 24 can thus rise or fall vertically in the guides, the holes 19 enabling it to pass the bosses 18, and carries at its upper surface upwardly projecting pins 28 arranged below the holes 14, and of such length as to pass through the holes to a plane above the upper surface of the heated plate when the pin plate 24 is raised.

Pivoted in two lugs 30 mounted on the wall of the casing 12 near the ends of the casing are two arms 32 which extend under the median line of the plate 24 and whose outer ends extend through apertures 34 in the side wall of the chamber. A U-shaped operating member 36 has its ends pivoted as at 38 to the casing and rests on the arms 32. The weight of the member 36 is nearly but not quite enough to balance the weight of the plate 24.

The blanks 38 to be heated are placed on the upper plate 11 which will be heated to the proper temperature by the units 16. When the operator desires a box toe he will reach over the member 36, depressing it with his forearm as he does so. This will raise the plate 24 and lift the blanks from the plate 11, enabling the operator to grasp one of them without any danger of touching the plate 11, and thereby injuring himself.

The apparatus is inexpensive, convenient in use, and avoids the trouble and danger heretofore characteristic of the shoemaking practice described.

Having described my invention, what I claim as new and desire to secure by Letters Patent of the United States is:—

1. An apparatus for heating articles, comprising means for supporting and heating an article, and secondary means constructed and arranged to support the article so that a hand may pick it up without touching the secondary means, said two means being relatively movable to transfer the heated article from the first said means to the other and being guided relatively to each other to promote such transference.

2. An apparatus for heating articles, comprising means for supporting and heating an article, means associated therewith for separating the heated article from said heating means, said two means being arranged to transfer the blank from one to the other in consequence of relative movement of the two means, and a movable element operatively connected to one of said means to cause such relative transferring movement, said element being arranged to be engaged and operated by an arm or hand extended to pick up the article from said separating means.

3. An apparatus for heating articles, comprising means for supporting and heating an article, a movable member arranged to be engaged by an arm or hand extended to pick up a heated article from the apparatus, said member being adjacent to but insulated thermally from said means, and means arranged to separate a marginal portion of the article from said heating means in consequence of relative movement between said two means, said member being connected to one of said means to cause such relative movement.

4. An apparatus for heating articles, comprising two confronting plates arranged one over the other, one of said plates being movable toward and from the other, the upper one of said plates having spaced holes and the lower plate having pins arranged in registration with said holes respectively, means arranged to heat the upper plate, and means arranged to move one of said plates toward the other to cause said pins to separate an article from the upper surface of the upper plate.

5. An apparatus for heating articles, comprising a foraminous plate for supporting the articles, heating means embedded in said plate, a plurality of pins connected together below said plate and in registration with the holes in the plate, the pins collectively and the plate being relatively movable to cause the pins to separate an article from the upper surface of the plate, and means for causing such relative movement of the pins and the plate.

6. A machine of the class described comprising a heating plate arranged to support an article, said plate having holes in it, and a member arranged under said plate and carrying pins registering with the holes, said member being movable to project the pins through the holes to lift a heated article from the heating plate whereby a marginal portion of the article may be conveniently grasped by a thumb and finger without touching the heating plate.

7. An apparatus for heating articles, comprising a foraminous plate for supporting and heating articles placed thereon, and means for separating the heated articles from said plate, said means including a plurality of spaced pins connected together below said plate and arranged in registration with the holes in the plate, said plate and said pins being relatively movable to project the pins through said holes.

8. An apparatus for heating articles, comprising two article-supporting structures constructed and arranged to have relative movement to transfer an article from one to the other, guiding means arranged to maintain said structures in coöperative relation for such relative transferring movement, and means arranged to heat one of said

structures exclusively of the other while both structures are in such relation as to execute relative transferring movement.

9. An apparatus for heating articles, comprising two article-supporting structures constructed and arranged to have relative movement to transfer an article from one to the other, guiding means arranged to maintain said structures in coöperative relation

for such relative transferring movement, 10 said structures being formed to have respectively relatively great and relatively small areal contact with the article, and means arranged to heat the structure that has the greater areal contact exclusively of the other. 15

In testimony whereof I have signed my name to this specification.

THOMAS LUND.
